UNITED STATES PATENT OFFICE.

WALTER S. LANDIS, OF WHITESTONE LANDING, NEW YORK, AND GUY H. BUCHANAN, OF WESTFIELD, NEW JERSEY, ASSIGNEES TO AMERICAN CYANAMID COMPANY, OF NEW YORK, N. Y., A CORPORATION OF MAINE.

PROCESS OF FUMIGATING.

No Drawing.

Application filed July 8, 1921. Serial No. 483,262.

To all whom it may concern:

Be it known that we, WALTER S. LANDIS and GUY H. BUCHANAN, both citizens of the United States, respectively, residing at 5 Whitestone Landing, in the county of Queens, State of New York, and Westfield, in the county of Union and State of New Jersey, have invented certain new and useful Improvements in Processes of Fumigating; 10 and we do hereby declare the following to be a full, clear, and exact description of the invention, such as will enable others skilled in the art to which it appertains to make and use the same.

15 This invention relates to a process of fumigating with highly poisonous fumigants, and has for its object to improve certain of the processes heretofore proposed and now in wide use, to the end that they 20 may be made more efficient and less dangerous than they are as at present practiced.

With these and other objects in view, the invention consists in the novel steps and combinations of steps constituting the process, all as will be more fully disclosed below and particularly pointed out in the claims.

In order that the present invention may be the more clearly understood, it is said:

25 In the fumigation of buildings, ships and other enclosed spaces with hydrocyanic acid gas for the purpose of destroying vermin and other pests, the common practice has been to determine the volume of the space to be fumigated and then to atomize or 30 vaporize into this space a suitable quantity of hydrocyanic acid.

The enclosed space, charged with the fumigant, is permitted to stand closed for a suitable length of time, usually one or two 40 hours, or even longer, in the case of certain special work, and is then opened up and the poisonous fumigant displaced by admission of fresh air from the outside. Where suitable means of ventilating the enclosed space 45 are at hand, the dissipation of the poisonous fumes is not a difficult problem, but in the case of ships and warehouses from five to twelve hours are usually required to effectively remove the poisonous gas and render 50 the space habitable. The long time necessary for clearing out the hydrocyanic acid fumes where facilities for ventilation are

limited, is at times a source of considerable expense. In the case of a cargo carrying steamship for example, it may mean a delay 55 in unloading or re-loading of the ship and a very considerable demurrage charge may accrue due to this tie-up of the vessel.

On the other hand, we have found a simple and expedient method of destroying the 60 residual hydrocyanic acid so as to eliminate it in a comparatively short time, thereby gaining the use of the space to be fumigated much more quickly.

In carrying out the present procedure, we 65 admit to the space after fumigating, a volatile aldehyde and ammonia. Aldehyde vapor, such as, for example, from acetaldehyde, reacts only very slowly with the dilute 70 gaseous hydrocyanic acid, but in the presence of a third material, such as ammonia for example, the reaction of the three products takes place very rapidly and is remarkably complete. For example, in carrying out this process we close up the space to be 75 fumigated comparatively tight, and introduce into this space sufficient hydrocyanic acid for effective fumigation. This quantity is such as to produce from 0.2 per cent up to one per cent by volume of hydrocyanic 80 acid gas in the space to be fumigated, and the application may be made either by generating the gas directly in the space, or by using liquid hydrocyanic acid which is applied through one of the several forms of 85 applicators in common use for this purpose.

We then leave the space closed up for one or two hours, or whatever time may be necessary to insure killing of the pest to be eliminated, at the end of which time we introduce for example one molecular weight of ammonia for each molecular weight of hydrocyanic acid used, and one and one-fourth molecular weights of acetaldehyde to each molecular weight of hydrocyanic 95 acid used. The ammonia may be introduced by atomizing very strong aqua ammonia, or preferably by direct expansion of anhydrous ammonia, while the acetaldehyde may be introduced through the same type of apparatus as is used for applying liquid hydrocyanic acid, as it is very volatile.

A reaction between the three constituents takes place, and in less than one hour it

will be found that the hydrocyanic acid has been destroyed and one may enter the room or space that has been fumigated with comparative safety. We have found that it makes no difference whether the ammonia or the aldehyde has been added first, or whether both are introduced simultaneously. Further, we have found that one need not adhere very closely to the above proportions of ammonia and aldehyde and in many cases we prefer to use said compounds in proportions of substantially more than one molecular weight of ammonia to one and one-fourth molecular weights of aldehyde.

15 We do not know the nature of the compounds formed and from such analysis as we have been able to make of the products of reaction collected in a closed space, we have been unable to identify the resulting 20 product with any of the catalogued organic compounds which one would expect. It is apparent that in the extremely dilute state and using anhydrous material, a new and complex reaction takes place producing new 25 results. We have also noticed that changing the proportions of the various reagents seems to have a marked effect upon the character of the products formed, but in no case have we been able to identify the result. It 30 is entirely different from that obtained by mixing these three ingredients together in more or less concentrated form in solution.

35 The reactions between anhydrous hydrocyanic acid and either the ammonia or the aldehydes alone are extremely slow and we have, therefore, found that it is possible to introduce either the ammonia or the aldehyde along with the hydrocyanic acid without interfering with the fumigation and then, after fumigation is complete, we may introduce the third reagent to destroy the hydrocyanic acid.

40 We have also found that various volatile aldehydes may be used, all of which seem 45 to exert this same reaction, but with different velocities, but we have obtained the most rapid destruction of the acid by the use of acetaldehyde.

50 The advantages of this process are that we can avoid the closing off of a fumigated space from use for a considerable period of time, owing to the relatively rapid neutralization, which not only avoids the disadvantage of non-use of the building or other 55 space, but also lessens the danger of fatal injury through some one inadvertently entering the space, which has been fumigated. Further, the formation of pockets of fumigant which are not removed in ordinary 60 ventilation is avoided, because the materials which we employ for the neutralization will diffuse wherever the original fumigant has gone.

65 It is obvious that those skilled in the art may vary the details of the procedure as

above disclosed, without departing from the spirit of the invention and therefore we do not wish to be limited to the above disclosure except as may be required by the claims.

What we claim is:

1. The process of fumigating with a poisonous fumigant which consists in introducing said fumigant into the space to be fumigated; and also introducing into said space after the fumigating action is completed an agent adapted to react with said fumigant to destroy the latter, substantially as described. 70

2. The process of fumigating a space with a poisonous fumigant which consists in first introducing into said space a fumigant and then after the fumigating action is completed, introducing into said space an agent adapted to react with and to destroy said fumigant; and also introducing into said space an agent adapted to accelerate the reaction between said first named agent and said fumigant, substantially as described. 75

3. The process of fumigating with a poisonous fumigant which consists in introducing said fumigant into the space to be fumigated; and subsequently introducing into said space an agent adapted to react relatively slowly with said fumigant to destroy the latter, together with an agent adapted to accelerate said reaction, substantially as described. 80

4. The process of fumigating with a poisonous fumigant which consists in introducing said fumigant, together with an agent adapted to react relatively slowly therewith to destroy said fumigant, into the space to be fumigated; and subsequently introducing into said space an agent adapted to accelerate the reaction between said first named agent and said fumigant, substantially as described. 100

5. The process of fumigating with a poisonous fumigant which consists in introducing said fumigant together with an accelerating agent into the space to be fumigated; and subsequently introducing into said space an agent adapted to normally react relatively slowly with said fumigant to destroy the same, substantially as described. 110

6. The process of fumigating with highly poisonous fumigants which consists in introducing hydrocyanic acid gas into the space to be fumigated; and also introducing into said space a volatile aldehyde, adapted to react with said gas to destroy the same, and an accelerating agent, substantially as described. 120

7. The process of fumigating with highly poisonous fumigants which consists in introducing hydrocyanic acid gas into the space to be fumigated; and subsequently introducing into said space a volatile aldehyde adapted to react relatively slowly with said gas to destroy the same, together with a 125

sufficient amount of ammonia to accelerate the reaction between the said gas and the said aldehyde, substantially as described.

8. The process of fumigating with highly 5
poisonous fumigants which consists in introducing hydrocyanic acid gas together with a volatile aldehyde into the space to be fumigated; and subsequently introducing into said space a sufficient quantity of ammonia 10
to accelerate the reaction between the said aldehyde and the said gas, to destroy the latter, substantially as described.

9. The process of fumigating with highly 15
poisonous fumigants which consists in introducing hydrocyanic acid gas into the space to be fumigated; and subsequently introducing into the said space ammonia and a volatile aldehyde which is adapted to normally react slowly with said gas but which in the 20
presence of said ammonia will react rapidly with the said gas to destroy the same, substantially as described.

10. The process of fumigating with highly 25
poisonous fumigants which consists in introducing hydrocyanic acid gas into the space to be fumigated; and subsequently intro-

ducing into said space ammonia and acetaldehyde to destroy the said gas, substantially as described.

11. The process of fumigating with highly 30
poisonous fumigants which consists in introducing hydrocyanic acid gas into the space to be fumigated; and subsequently introducing into the said space ammonia and acetaldehyde in substantially the proportions of 35
one molecular weight of ammonia and one and one-fourth molecular weights of acetaldehyde to each molecular weight of hydrocyanic acid used, substantially as described.

12. The process of fumigating with highly 40
poisonous fumigants which consists in introducing hydrocyanic acid gas into the space to be fumigated; and subsequently introducing into said space ammonia and aldehyde in the proportions of substantially more 45
than one molecular weight of ammonia to one and one quarter molecular weights of aldehyde, substantially as described.

In testimony whereof we affix our signatures.

WALTER S. LANDIS.
GUY H. BUCHANAN.
